FRINGE.

No. 18,365.

Patented June 5, 1888.

UNITED STATES PATENT OFFICE.

GEORGE S. HENSEL, LOUIS D. VALETTON, AND FRANK E. COOK, OF PHILADELPHIA, PENNSYLVANIA, ASSIGNORS TO THE HENSEL, COLLADAY COMPANY, OF SAME PLACE.

DESIGN FOR FRINGE.

SPECIFICATION forming part of Design No. 18,365, dated June 5, 1888.

Application filed April 28, 1888. Serial No. 272,202. Term of patent 7 years.

To all whom it may concern:

Be it known that we, GEORGE S. HENSEL, LOUIS D. VALETTON, and FRANK E. COOK, citizens of the United States, residing in the 5 city and county of Philadelphia, State of Pennsylvania, have invented and produced a new and original Design for Fringes, reference being had to the accompanying photograph forming part thereof.

10 The leading features of our design for fringe are, first, flowers on the head, and, next, festoons at the base thereof.

In the photograph, A represents the head of a fringe, and B the flies thereof. On the 15 head are daisies 1, with stems 2, which form a continuous line of flowers throughout the head. At the base of the head is a line of festoons, 3.

We claim—

1. In a design for a fringe, a head portion having thereon the representation of daisies 20 with stems laterally continuous thereof, substantially as shown and described.
2. The design for a fringe herein shown and described, consisting of a head portion having thereon the representation of flowers with connecting-stems, and at its base a line or row of festoons, and flies B pendent from said head, substantially as described.
